(57) **CLAIM**

We claim the ornamental design for a suitcase, as shown and described.

DESCRIPTION

FIG. 1 is a perspective view of the suitcase;

FIG. 2 is a front view of the suitcase as shown in FIG. 1;

FIG. 3 is a left side view of the suitcase as shown in FIG. 1;

FIG. 4 is a right side view of the suitcase as shown in FIG. 1;

FIG. 5 is a top view of the suitcase as shown in FIG. 1;

FIG. 6 is a bottom view of the suitcase as shown in FIG. 1; and,

FIG. 7 is a back view of the suitcase in accordance with the present invention.

The dotted lines shown in FIGS. 1 and 3 do not form part of the claimed design.
